CONTAINER

Millard Lemar Snyder, York, Pa.

Application June 9, 1931. Serial No. 543,190

9 Claims. (Cl. 206—46)

This invention relates to the class of special receptacles and provides a container, the general object of which is to protect frangible objects, particularly food-stuffs such as cakes or pies from damage incidental to their handling, as well as atmospheric deterioration such as staleness or the absorption of excess moisture.

A more specific object of the invention is to provide a container for cakes, pastry, and the like, comprising telescoping members forming a chamber, including a rigid base for supporting the object, a non-hygrosopic and preferably transparent cover, the telescoping margin of which forms a seal with the base and/or a similar stiff protective cover fitting the base in like sealing manner.

Other objects of the invention will appear as the following description of several practical embodiments thereof proceeds.

In the drawings in the several figures in which similar characters have been used to designate identical parts:

Figure 1 is a cross section through one form of the invention in which two cooperating elements are employed to form a casing or cover for the object to be protected;

Figure 2 is a similar view illustrating the use of three elements;

Figure 3 is a bottom plan view of that form of the invention shown in Figure 2;

Figure 4 is a perspective view of the "Cellophane" cover;

Figure 5 is a modified form of the invention adapted to receive a pie;

Figure 6 is a perspective view of the intermediate member used in that form of the invention illustrated in Figure 5;

Figure 7 is a perspective view of the base member shown in Figure 5;

Figure 8 is a vertical section through another form of the invention in which no transparent member is employed; and

Figure 9 is a perspective view of the cover portion of the container shown in Figure 8.

Referring now in detail to the several figures, and first advertiring to that form of the invention shown in Figures 1 to 4, inclusive, the invention in its broadest form is essentially completed by the use of the two elements 1 and 2, one being a base member preferably pressed from a heavy grade of paper stock so as to be sufficiently rigid to support the object, for instance, a cake, placed thereupon. The member 1 is preferably formed with a flaring flange 3 upon which it rests. The top portion of the base member

being unsupported, is relatively resilient and serves to protect the cake from shock.

The element 2 is of dished shape sufficiently deep to form a chamber enclosing the cake or other objects supported upon the base forming a 60 cover therefor. Said cover telescopes at its margin over the flaring flange 3 and for the purpose of providing a sealed joint at this point the cover is provided with a stiffening ring 4 pasted or otherwise united to the cover and having the 65 same flare as that of the flange 3, so as to enable the cover 2 to fit wedgingly upon the flange of the base. It is preferred that the cover 2 be made of non-hygrosopic material, such for instance as "Cellophane" which has the added at 70 tribute of transparency so that the contents of the package is made visible. A container using only the base and cover members as above described is ideal for the display of goods in a store window or for the dispensing of the protected object at 75 soda fountains or in cafeterias.

A cover of "Cellophane" or the like is hardly sufficiently stiff to protect the contained object for shipping or while being taken home from the store by a customer. It is therefore preferred 80 to add the third element comprising a protective casing 5 of the same general shape as the "Cellophane" cover but slightly deeper so as to provide a slight clearance between said casing and the "Cellophane" cover beneath. The casing 85 preferably has the same flare as the flange 3 so as to nest snugly over the reinforcing ring 4 of the "Cellophane".

It is usually preferred to make the flare of the telescoping portions of the several parts so slight 90 as to constitute a sticking taper, so that when the several parts are nested the package can be held with impunity without risk of falling apart. However, if desired, either the "Cellophane" unit or the outer protective cover may be provided 95 with metal lugs or ears 6 which may be bent over the flange of the base so as to secure the parts in a positive manner.

Figure 8 shows that the invention also contemplates using the base member and outer casing without the intermediate "Cellophane" protector.

In Figures 5, 6 and 7, a form of the invention is shown adapted for the reception and protection of a pie. The base member 7 is provided 105 with the flared marginal flange 8 similar to the flange shown in the first described form, the central portion of the base being slightly dished so that the pie is in effect, suspended. This construction adds to the rigidity of the base and 110

- reduces the force of shocks to the container which might tend to shatter the pie. Although a three-element construction may be used with this base, similar to the construction described in connection with Figure 1, it is preferred to use a two-element construction including the frusto-conical outer casing 9, open at its upper as well as at its lower end and provided with a "Cellophane" or other transparent as well as hygroscopic shell
- 5 11. The marginal portions of said shell may extend between the flange of the base and the casing 9 and be clamped therebetween when the casing is wedgingly applied to the base. The "Cellophane" shell may if desired, be pasted to the inside of the casing. As an added protection against rupture of the "Cellophane" shell, the top membrane thereof may terminate at a distance below the upper edge of the casing 9 as shown in Figure 5.
- 10 15. With this form of container, the pie is visible both through the "Cellophane" and the open end of the outer casing. At the same time it is suspended at a spaced distance from the planes embracing the upper and lower edges of the outer container whereby it is best protected from injury.
- 20 30. In Figures 8 and 9 is shown a form of the invention in which the base is not flared, the telescoping parts of the base 12 and cover 13 making a close cylindrical fit. In view of the fact that the element of the sticking taper is not present in this form, it is probably indispensable that the cover should be provided with the lugs 6.
- 25 35. It will be understood that the above described modifications illustrate only a few of the specific forms in which the invention can be embodied and that the details of construction as shown and described are not to be construed as limitative in their effect upon the scope of the invention as claimed.
- 40 45. **What I claim is:**
1. Container comprising a relatively rigid inverted cup-shaped bottom and a relatively flexible inverted cup-shaped cover, the latter having a peripheral reinforcing ring, said bottom and said cover having their open ends facing the same direction, with the marginal portion of the cover including the zone of the reinforcing ring telescopically engaging the sides of the bottom member in sealing relation.
  2. Container comprising an inverted cup-shaped bottom member formed with a downwardly flared peripheral flange, an inverted cup-shaped cover member having a reinforcing ring at its marginal portion correspondingly flared, said cover member and said bottom member having their open sides facing the same direction, and said cover member in the zone of said reinforcing ring engaging the flange of said bottom member in sealing relation.
  3. Container as claimed in claim 2, the bottom member being relatively rigid and the cover member above said reinforcing ring being relatively non-rigid.
  4. Container comprising a plurality of inverted cup-shaped members adapted to be arranged in nested relation with their open sides in the same direction, including a bottom member having a downwardly extending peripheral flange, an intermediate member of greater depth
- than said bottom member and of relatively flexible material having a reinforcing ring at its margin, and an outer protective member of at least as great depth as said intermediate member, the flange of said bottom member, the reinforcing ring of said intermediate member and the marginal portion of said outer member telescoping in sealing relation.
5. Container comprising a bottom member having a downwardly extending peripheral flange, and a cover member having sides of greater width than the depth of the flange of said bottom member adapted to nest over said bottom member with its sides in sealing relation to the flange of said bottom member, said cover member being provided with a transverse membrane forming a top, the sides of said cover member and the flange of the bottom member being correspondingly flared, to engage with a sticking taper, the transverse membrane extending within said cover member in a plane intermediate its top and lower edges.
- 80 85. 6. Container comprising a bottom member having a downwardly extending peripheral flange, and a cover member having sides of greater width than the depth of the flange of said bottom member adapted to nest over said bottom member with its sides in sealing relation to the flange of said bottom member, said cover member being provided with a transverse membrane forming a top, the transverse membrane extending in a plane intermediate the top and lower edges of said cover member and being 90 95. 100. 105. 110. 115. 120. 125. 130. 135. 140.
7. A container comprising a bottom having a downwardly extending outwardly tapered peripheral flange, an intermediate member having sides of similar tapered construction and adapted to nest over said flange with its nested portion in tapered sealing relation with said flange, a cover member having sides of similar tapered construction adapted to nest over said intermediate member with its nested portion in tapered relation with said intermediate member.
8. A container comprising a bottom having a downwardly extending outwardly tapered peripheral flange, an intermediate member having portions of comparatively fragile material, and being of similar tapered construction adapted to nest over said flange in tapered sealing relation therewith, a protective cover of greater depth than said intermediate member having sides of similar tapered construction and adapted to nest over said flange in tapered sealing relation with the bottom portion of said intermediate member.
9. A container comprising a bottom having a downwardly extending outwardly tapered peripheral flange, an intermediate member having portions of comparatively fragile transparent material, and being of similar tapered construction adapted to nest over said flange in tapered sealing relation therewith, a protective cover of greater depth than said intermediate member having sides of similar tapered construction and adapted to nest over said flange in tapered sealing relation with the bottom portion of said intermediate member.
